UNITED STATES PATENT OFFICE.

NICHOLAS BOREN, JR., OF HAUBSTADT, INDIANA.

CHURN-POWER.

SPECIFICATION forming part of Letters Patent No. 229,947, dated July 13, 1880.

Application filed May 21, 1880. (Model.)

To all whom it may concern:

Be it known that I, NICHOLAS BOREN, Jr., of Haubstadt, in the county of Gibson and State of Indiana, have invented a new and useful Improvement in Churn-Motors, of which the following is a specification.

My invention consists in a novel arrangement and combination, with the churn-dasher rod, of a series of shafts and band-wheels and a drum and weight and connections, whereby provision is made for obtaining an increased velocity of the dasher, as hereinafter described.

In the accompanying drawings, Figure 1 is a top view, partly in section, of an apparatus embodying my improvements. Fig. 2 is a side view of the same.

Similar letters of reference indicate corresponding parts.

A represents the floor of a room in which the apparatus is used, and C represents a frame-work supporting the working parts, which frame-work rests upon the floor A. B represents a standard extending upward from the floor A, and provided with an arm, b, to which is attached a pulley, D, for the purpose hereinafter described.

In the frame-work C is journaled a shaft, E, which carries at one end a crank, G, and at the other end a band-wheel, H. This band-wheel is provided with a crank-pin, to which is connected the upper end of a pitman, i, the lower end of which is connected to a treadle, J, so that the shaft E may be turned by means of either the crank or the treadle.

On the shaft E is a drum, K, which works loosely thereon, except when engaged by a clutch, L, fixed to said shaft. To the drum K is attached one end of a cord, M, which passes over the pulley D and has a weight, P, attached to its other end. The clutch L is provided with a spring, l, for holding it engaged with the drum K.

The band-wheel H is provided with a brake consisting of a roller, r, carried by the short arm of a lever, R, pivoted in the frame-work C, and having its long arm formed into a ring and engaging with a spiral groove in a vertical pin, Q, having its seat in the frame-work C. By turning the pin Q the tension of the

brake is regulated and the speed of rotation 50 of the wheel H is governed thereby.

From the wheel H a band, s, passes to a pulley, s², carried by a shaft, S, which shaft also carries a wheel, s³. From this wheel a band, t, passes to a pulley, t², carried by a 55 shaft, T, which shaft also carries a wheel, t³. The wheel t³ is provided with a crank-pin, to which is connected the lower end of a pitman, v, the upper end of which is connected to one side of a slide, V, working in vertical 60 ways attached to the frame-work C. To the other side of the slide V is connected the dasher-rod w of a churn, W, of any suitable description.

The spoke of the wheel t³, to which the pitman v is connected, is provided with a number of holes arranged in a radial direction, so that by changing the crank-pin t⁴ from one hole to another the stroke of the dasher-rod may be lengthened or shortened.

Near the periphery of the wheel t³, diametrically opposite the point of connection of the pitman v, is a counterbalance-weight, T², by means of which the wheel t³ is enabled to act as a fly-wheel, and a regular and uniform 75 motion of the apparatus is insured.

The shaft E is turned so as to wind the cord M on the drum K. By disengaging the clutch L the drum may be turned independently of the shaft. As the weight P descends 80 motion is communicated to the shaft E, and thence, through the wheels, bands, and pulleys before described, to the slide V, so as to impart a very rapid vertical reciprocating motion to the dasher-rod w.

Having thus fully described my invention, I claim as new and desire to secure by Letters Patent—

1. The combination, with a churn and its dasher-rod, of the drum K and its weighted 90 cord, the clutch L, the shafts E, S, and T and their wheels and connecting-bands, and the pitman v and slide V, as herein shown and described.

2. The combination, with the band-wheel H, 95 of the adjustable brake consisting of the roller r, lever R, and spirally-grooved pin Q, as herein shown and described.

3. The standard B, provided with the arm b and carrying the pulley D, in combination with the weighted cord M, the drum K, and the churn mechanism, as herein shown and 5 described.

4. The wheel t³, provided with the counter-balance T², and with a series of holes arranged in a radial direction, in combination with the crank-pin t⁴, pitman v, and the dasher-rod and 10 churn mechanism, as herein shown and described.

5. The slide V, working in vertical ways attached to the frame C, in combination with the pitman v, attached to one side, and the dasher-rod attached to the other side, as herein 15 shown and described.

NICHOLAS BOREN, JR.
